UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed September 5, 1922. Serial No. 586,063.

To all whom it may concern:

Be it known that I, JESSE A. B. SMITH, a citizen of the United States, residing in Stamford, in the county of Fairfield and State of Connecticut, have invented certain new and useful Improvements in Typewriting Machines, of which the following is a specification.

The present invention relates to the mechanisms in a typewriting machine for returning the carriage thereof, and for releasing the pressure device, for the placement and removal of work-pieces, and restoring the pressure device for its necessary function. More particularly, the invention has to do with means for operating these mechanisms to expedite and simplify the placement and holding of bills, cards and notices on which the entries to be typed are short, and which, when written in considerable quantity, involve frequent unsetsetting and resetting of the work-pressing or holding devices.

The pressure devices, which hold the work-pieces to the platen, have heretofore been released, for removal and placement of work-pieces, by means of a finger-piece. After the new work-piece has been inserted, the pressure or holding device has been restored by again manipulating the same finger-piece. In filling in certain printed forms or notices, it is required to typewrite but a single line, and the manipulation of the pressure-releasing and restoring device occupies a disproportionate part of the operator's time and attention.

An object of the present invention is to overcome this difficulty and minimize or eliminate the time and effort heretofore consumed in first releasing and subsequently restoring the work-holding device. To this end it is contrived to release the work-holding device, hold it released, and subsequently to restore it to hold the newly inserted work, without demanding either attention or effort on the part of the operator, or consuming his time. This result is gained by causing the work-holding device to release the work in the time that is necessarily consumed by the returning movement of the paper-carriage, so that no time is consumed for the work-releasing operation between carriage-strokes; advantage being taken of the circumstance that the work does not need to be line-fed, wherefore there is no need to

press the work against the platen when it is not being typed upon. This result is accomplished by a treadle which returns the carriage and concomitantly releases the work-holder and subsequently holds the work-holder in released condition after the carriage has completed its return stroke, leaving both hands of the operator free, one to withdraw the released work, and the other to insert the fresh work between the platen and the work-holder while the latter is maintained by the treadle in released condition; the work-holder being self-restored upon relief of the treadle from pressure, so that the operator is relieved from manipulating the work-holder at any stage.

Other features and advantages will hereinafter appear.

In the accompanying drawings,

Figure 1 is a view in side elevation of the upper part of a typewriting machine, showing the connections thereto of the present invention.

Figure 2 is a view in front elevation of the upper right-hand portion of the machine, showing the connections of the present invention thereto and the treadle for operating the same.

Figure 3 is a view in side elevation of a machine embodying a modified form of the invention.

The platen 10 is mounted on an axle 11 journaled in the side pieces 12 of the platen carriage. The platen carriage, at the rear thereof, is supported and runs on a rail 13 on the main frame 14 of the machine; and at the front thereof has a roller-bearing 15 on the main frame. The carriage is provided with the usual paper-table 16 upon which bills, cards or work-pieces may be fed around the platen to the printing position. The work-pieces may, however, be inserted bottom end first at the front of the platen.

Fixed to the side pieces of the carriage frame is a shaft 17 having pivotally mounted thereon arms 18, which carry rear devices 19 to press the work against the platen, and arms 20, which carry front pressure devices 21. The arms 18 form bell-cranks with arms 22, shown as depending from the shaft 17; and the arms 20 form bell-cranks with arms 23, likewise shown as depending from the shaft 17. The arms 22 and 23 engage on opposite sides of flats 24 on a rock-shaft 105 110

25. Springs 26 and 27, respectively, hold the arms 18 and 20 in Figure 1 position, with the pressure devices against the platen, and restore the pressure or work-holding devices to such position when free to do so. In Figure 1, with the pressure devices against the platen, the arms 22 and 23 of the bell-cranks are shown as engaging the flats on the shaft 25. On turning the rock-
10 shaft 25, however, the flattened portions of said shaft force apart arms 22 and 23, depressing the arms 18 and 20 to release the pressure devices. For effecting such movement of the shaft 25 to release the pressure
15 devices, there is fast to the shaft 25 an arm 28, which connects by a link 29 to an arm 30 pivoted on a shaft 31 journaled in the right-hand side piece of the carriage; the shaft 31 having also fast thereto an arm 32
20 carrying a finger-piece 33. Upon movement of the finger-piece 33 from full line to dotted line, Figure 1, position, the link 29 is drawn up to rock the shaft 25 and release the pressure devices. The parts thus far de-
25 scribed are found in the standard Underwood typewriting machine.

For concomitantly releasing the pressure devices and returning the carriage, the following mechanism is provided. Fast to the
30 front rail of the carriage, at the right-hand end thereof, is a bracket 34 on which is journaled a pulley 35. Fast to the main frame of the machine, at the right-hand end thereof, is a bracket in the form of an arm
35 36 extended to the right and having at its end an ear 37, in which is journaled a pulley 38. A cord 39 connects at 40 to the pressure-device-releasing lever 32, and thence is led rearward to and around the pulley 35,
40 and to the right to and around the pulley 38 downward to a treadle 41, to which it connects at 42. The treadle 41 is pivoted at 43 to the floor or other suitable place for operation by the operator's foot. When
45 the treadle is depressed, it effects a movement of the roll-releasing arm 32, which may be determined by a stop 51 on the side piece of the carriage, thus permitting the springs 26, 27 to restore the pressure de-
50 vices 19, 21 when permitted by the treadle, after the insertion of the fresh work-piece, preparatory to typing a line thereon. Further forward movement of the arm 32 is prevented. Movement of the treadle more-
55 over serves to return the carriage to the right until it is arrested by its margin stop.

In Figure 3, the cord 39, after passing over the pulley 35, is led down and connected to a drum 44, shown as journaled at 45 on the
60 side of the main frame of the machine, but which may be journaled on any other suitable standard. Fast to the drum 44 is a pinion 46 meshing with a larger pinion or gear 47 fast on a shaft 48, to which is also
65 fast an operating arm 49 having a handle

50. A forward movement of the handle 49 from normal or Figure 3 position causes rotation of the drum 44 in such direction as to draw upon the cord 39 and release the pressure device in the same manner as in the structure at Figures 1 and 2. The gearing is so proportioned as to effect the necessary length of carriage-return movement most conveniently.

Variations may be resorted to within the scope of the invention, and portions of the improvements may be used without others.

Having thus described my invention, I claim:

1. In a typewriting machine, the combination with a platen and a letter-feeding carriage therefor, of a releasable work-holding pressure device bearing against the platen, means effective without requiring attention or use of either hand of the operator for automatically releasing the work from the control of the pressure device, and for maintaining the pressure device released to permit the operator to withdraw the typed work-piece with one hand, and insert a fresh work-piece with the other hand, including a carriage-returning pedal, means for connecting said pedal to said pressure device to release the same simultaneously with the return of the carriage and maintain the pressure device released until after the completion of the return of the carriage, and means for mechanically restoring the work-holder upon the release of the pedal.

2. In a typewriting machine, the combination with a platen and a letter-feeding carriage therefor, of a releasable work-holding pressure device bearing against the platen, means effective without requiring attention or use of either hand of the operator for automatically releasing the work from the control of the pressure device, and for maintaining the pressure device released to permit the operator to withdraw the typed work-piece with one hand, and insert a fresh work-piece with the other hand, including a movable member, a cord attached thereto, a pedal connected to draw on the cord to release the pressure device and return the carriage, and hold the pressure device thereafter released for insertion of a fresh work-piece, and means dependent upon the release of the pedal for restoring the pressure device upon the platen.

3. In a typewriting machine, the combination with a platen and a letter-feeding carriage therefor, of a releasable work-holding pressure device bearing against the platen, means effective without requiring attention or use of either hand of the operator for automatically releasing the work from the control of the pressure device, and for maintaining the pressure device released to permit the operator to withdraw the typed work-piece with one hand, and insert a

fresh work-piece with the other hand, a 40
pedal, a cord, a drum to which the cord is
attached, an arm for turning the drum to
draw on the cord to effect both a releasing
movement of the pressure device and a
return movement of the carriage, said drum,
cord and arm holding the pressure device
released, and means effective upon the
release of the pedal from pressure for restor-
ing said pressure device to the platen.
5 45

5. In a typewriting machine, the combina-
tion with a platen and a letter-feeding car-
riage therefor, of a releasable work-holding
pressure device bearing against the platen,
means effective without requiring attention
or use of either hand of the operator for
automatically releasing the work from the
control of the pressure device, and for main-
taining the pressure device released to per-
mit the operator to withdraw the typed
work-piece with one hand, and insert a fresh
work-piece with the other hand, a lever
pivoted to swing forward for releasing the
pressure device, a cord attached to the lever,
25 a pulley on the carriage forward of the lever
and over which the cord is passed, a pulley
on the main frame over which the cord is
also passed, a pedal, and a device connected
to the lever for enabling the pedal to draw
30 the same to actuate the lever for releasing
the pressure device, and thereupon to draw
upon the lever to return the carriage, and
means dependent upon the release of the
pedal for restoring the pressure device to
35 the platen.
6 35

5. In a typewriting machine, a platen, a
carriage therefor movable in letter-feed and
return directions, means for holding work-
pieces to the platen, means operable by the

operator without using either hand for mov-
ing said holding means from the platen for
insertion and withdrawal of work-pieces,
means connected to said last-mentioned
means for actuating the same and returning
the carriage, and means for restoring said
work-holding means to the platen upon the
release of the actuating means by the oper-
ator after the completion of the return of
the carriage.
10 45

6. In a typewriting machine, a platen, a 50
carriage therefor, spring-pressed means for
holding work-pieces to the platen, a device
for moving said holding means from the
platen for insertion of a work-piece, a stop
on the carriage for limiting such release
movement of said device, means operable by
the operator without using either hand and
connected to said device for moving the same
to the stop to release the holding means, and
for concomitantly moving the same with the
carriage in return direction, and means ef-
fective after the return of the carriage for
restoring said work-piece to the platen upon
the release of said moving device.
15 55

7. In a typewriting machine, the combina-
tion with a traveling carriage, a revoluble
platen therein, and feed-rolls co-operating
with the platen, of manual means for con-
comitantly line-spacing the platen and re-
turning the carriage, and means operable by
the operator without using either hand for
concomitantly casting off the feed-rolls and
returning the carriage without line-spacing
the platen, said two means being operable
independently of and without interference
with each other.
